[57] CLAIM

The ornamental design for a collapsible support stand for a golf club bag, as shown.

DESCRIPTION

FIG. 1 is a side elevational view of the collapsible support stand for a golf club bag embodying the features of my new design;

FIG. 2 is a plan view thereof;

FIG. 3 is a bottom view thereof;

FIG. 4 is a perspective view thereof looking from above and the rear;

FIG. 5 is a front view thereof; and

FIG. 6 is a perspective view of the support stand in its collapsed position looking from above and the rear.

FIG. 1

FIG. 2
